Fig. 4

Fig. 5

Fig. 6

Fig. 7

Fig. 8

FIG. 1 is a side elevation of a rigid molded cover for a snowmobile showing my new design; the opposite side is identical to the side shown;

FIG. 2 is a top view of the cover;

FIG. 3 is a front view of the cover;

FIG. 4 is a rear view of the cover;

FIG. 5 is a side elevation of a modified form of the invention in which the cover is formed of two longitudinally-split halves removably joined together;

FIG. 6 is a top view of the cover shown in FIG. 5;

FIG. 7 is a front view of the cover shown in FIG. 5; and

FIG. 8 is a rear view of the cover shown in FIG. 5.

I claim:

The ornamental design for a rigid molded cover for a snowmobile, substantially as shown and described.
